Ms. 370

Micajah C. Burleigh of Somersworth, N.H.

Letters Patent No 370. Dated May 13, 1857

The schedule referred to in these Letters Patent and making part of the same

To all whom it may concern:

Be it known, that I, Micajah C. Burleigh of Somersworth in the County of Strafford and State of New Hampshire, have invented a new design for Stove doors, and panels, and I do hereby declare that the following is a full, clear and exact description of the same, reference being had to the accompanying drawings forming part of this specification in which

Fig: 1, is a front view of a stove door of my improved design.

Fig: 2, is a transverse section showing the ornaments and mouldings in profile. -

Similar letters of reference indicate corresponding parts in each of the several figs. -

The front of the door is surrounded by a fillet A bevelled inwards. Within the fillet is a small space in the plate which has a flat surface. In the centre there is a raised panel surrounded by an edge B, at the foot of which there is a small head C. In the centre of the panel there is a raised circular shield D, on which is represented in bas relief, a hand holding a full blown rose on whose stem there are a bud and leaves. The shield is surrounded by a bead E, from which radiate rays F, terminating at a short distance within the border of the panel;

This design by having its size varied is applicable to any stove door or panel

What I claim as my invention and desire to secure by Letters Patent is

The general arrangement and configuration of the ornaments and mouldings A, B, C, D, E, F, substantially as herein shown.
